UNITED STATES PATENT OFFICE.

TONY C. CLEMMONS, OF ENSLEY, ALABAMA.

MAINTAINED GUN.

1,289,665.

Specification of Letters Patent. Patented Dec. 31, 1918.

Application filed October 7, 1918. Serial No. 257,138.

To all whom it may concern:

Be it known that I, TONY C. CLEMMONS, a citizen of the United States, residing at Ensley, in the county of Jefferson and State of Alabama, have invented certain new and useful Improvements in Mounted Guns, of which the following is a specification.

My invention relates to improvements in mounted guns, and the object of the invention is to provide a gun mounted on a pivot which can be raised or lowered by means which will hereinafter be more fully described.

In the drawings:

15 Figure 1 is a top plan view of the gun with the invention applied thereon, and Fig. 2 is a side elevation of the same.

Referring to the drawings like numerals designate like parts in the various drawings. 20 The gun 1 is mounted on a pivot 2 which rests on the brace 3 fastened to the base of the gun 4. The pivot 2 can be raised or lowered by means of screw-jack 5 actuated by the crank-arm 6.

25 Braces 7 and 8 are secured on the base 3 and have bolted on their ends the two supports 9 and 10 on which stand two screw-jacks 11 and 12, the screw-jack 11 being used to raise or lower the gun to obtain the desired range, and the screw-jack 12 is secured

on the support 10 and fastened at its other end to the barrel of the gun by suitable means as at 13. The said screw-jack is actuated by the crank-arm 14.

From the foregoing it is thought that the 35 construction of my invention will be clearly understood, and therefore a more extended explanation has been omitted.

What I claim as new, is,—

1. A gun, a pivot-support therefor, means 40 for raising and lowering said support, and independent means upon opposite sides of said pivot-support for raising and lowering the gun to obtain the desired range.

2. A base, a pivot-support rising therefrom, jack screws, one for raising and lowering said pivot-support and others for raising and lowering the gun upon opposite sides of said pivot-support, braces on the base, supports secured to said braces, and crank arms 50 for actuating said jack screws independently of each other.

In testimony whereof I affix my signature in the presence of two witnesses.

TONY C. ^{his} CLEMMONS.
